Fig. 2.

UNITED STATES PATENT OFFICE.

JOSEPH ARONOFF, OF NEW YORK, N. Y.

FAN.

Application filed June 19, 1922. Serial No. 569,462.

To all whom it may concern:

Be it known that I, JOSEPH ARONOFF, a citizen of the United States, and resident of the city of New York, borough of Manhattan, county of New York, and State of New York, have invented a new and Improved Fan, of which the following is a full, clear, and exact description.

My invention relates to a fan, and aims to provide certain new and useful improvements in connection with a device of this character.

It is an object of the present invention to provide a fan which is movable with respect to a supporting element, so that a blast of air will be directed in various directions.

It is a further object of the present invention to construct a fan which will involve a mechanism permitting of its moving with respect to a supporting element for the purpose set forth in the preceding paragraph, but in which a further means will be provided which will serve to prevent this movement.

Another object of the present invention is that of constructing a device of the character stated which will preferably employ a plurality of fans, and means for driving the same, which latter means may be actuated to operate all of the fans synchronously, or to permit of an actuation of one or more of the same independent of the others.

Still another object of my invention is that of providing a fan in which the angle at which the blast of air is delivered may be varied according to the desire of the operator.

Among further objects of my invention are that of providing a fan embodying a relatively simple construction capable of being placed on the market at a nominal figure, the fan proper being adapted to be positively moved with respect to the supporting element therefor.

With these and further objects in mind my fan consists essentially of a motor, and a support for the motor, together with a fan, and means connecting the fan with the motor, the said fan proper being capable of being moved with respect to the motor mounting.

Reference is had to the attached sheets of drawings as illustrating one practical em-

bodiment of my invention, and it will be seen in these views that;

Figure 1 is a sectional side elevation of a fan embodying my improved construction.

Figure 2 and Figure 3 are sectional plan views taken along the lines 2—2 and 3—3 and in the direction of the arrows indicated in Figure 1.

Figure 4 is a transverse sectional view taken along the line 4—4 and in the direction of the arrows also indicated in Figure 1, and

Figure 5 is a fragmentary sectional view of a detail of the operating mechanism forming a part of my improved construction and taken along the line 5—5 and in the direction of the arrows indicated in Figure 2.

In these views the reference numeral 11 indicates the motor which may be of any desired type and construction and which is enclosed within a supporting housing 12, a gear housing 13 being formed adjacent the outer end of the housing 12 and being rotatably supported thereby, by any suitable means such as that of providing an outwardly extending annular flange 14 adjacent the upper edge of the housing 13, and the provision of a ring plate 15 at the lower end of the housing 12, and extending inwardly therefrom, thus providing a ball race within which an annular series of balls 16 may be disposed to freely permit of the turning of the housing 13 with respect to the housing 12.

Now with a view of positively rotating one housing with respect to the second of the same it will be noted that I preferably form teeth 17 in the upper edge of the housing 13, and these teeth in aggregate provide an annular rack which is engaged by the teeth of a gear 18 carried by the housing 12. The shaft 19 of the motor is extended into the housing 13 and its body carries a worm 20 with which a worm wheel 21 co-operates. This latter element is mounted upon a shaft 22 which in turn carries a gear 23 and the latter meshes with the gear 18 so that upon the motor shaft 19 being rotated, the worm 20 and the shaft 22 will be accordingly rotated, thus causing a corresponding movement to be transmitted from the gear 23 to the gear 18 and thus to the rack provided by the teeth 17 so that the operation of the

motor 11 will cause the housing 13 to be positively rotated with respect to the housing 12.

Now with a view of providing means which will serve to prevent a movement of the housing 13 with respect to the housing 12, if an operator desires to prevent this action, it will be seen that one end of the shaft 22 is supported upon a crank 24 lying within the housing and having its outer end extending beyond the same, whereby upon the arm 25 being rocked the crank arm will be correspondingly moved thus oscillating one end of the shaft 22 incident to the provision of a ball and socket support 26, at its opposite end. In this connection attention is invited to Figure 5 which shows in full and dotted lines, respectively, the position with which the wheel 21 may assume with respect to the worm 20 and it will be obvious from these views that an operator may cause the crank 24 to assume a position which will cause a positive co-operation between the wheel 21 and the worm 20, but upon it being desired to prevent a rotation of the housing 13 with respect to the housing 12 a shifting of the crank 24 will achieve the result desired in that it causes the worm wheel 21 to move out of engagement with the worm 20 or in other words, to the position shown in dotted lines in the view aforesaid referred to.

It will further be seen that the motor shaft 19 carries a crown gear 27 and a plurality of brackets 28 are associated with the housing 13 in a manner hereinafter described, to support fan shafts 29 in suitable bearings provided for this purpose. These shafts carry adjacent their outer ends suitable fans 30 and incident to the association of burr gears 31 with the opposite ends of each of these shafts, and the co-operation of these latter gears with the crown gear 27 it will be obvious that upon the motor 11 being actuated that the crown gear will effect an operation of the fans 30 to produce blasts of air.

If it is now desired to dispose one or more of the fan shafts 29 at an angle with respect to the axis of housing 13 different from that shown in Figure 1 this may be accomplished due to the peculiarity of the bracket mounting. In other words it will be noted that each of the brackets 28 is provided with a slotted portion 32 in its base and extending through this slotted portion is a shank of a wing bolt 33, which latter has the inner end of its shank screw threaded, and associated with the said housing 13. Thus due to the fact that the lower end of the housing 13 is curved, and further for the reason that the inner contour of each of the brackets 32 corresponds to the outer contour of this curved portion, one or all of the brackets can be slid downwardly or moved up-

wardly by simply releasing its associated clamping member i. e. the bolt 33, and swinging the bracket to the position desired subsequent to which the same can again be affixed to the housing 13.

This action of the parts will not however cause a breaking of the driving connection existing between the motor shaft 19, and the shafts 29 due to the provision of the burr gears 31 and the crown gear 27. Thus it will be obvious that a swinging of any one of the shafts 29 with respect to the housing would merely result in the teeth of the gear 31 being slid with respect to the teeth of the gear 27 so that this portion, in angularity to the shafts 29 and 19 will not in any way interfere with the driving of the former from the latter. It is also to be noted in this connection that an efficient support for each of these shafts and each of its saddle members 34 are swingingly carried at a point 35 by the brackets 36, it being noted that this point of connection, which may be established by suitable pins, is in line with the center of the burr gear. Thus each of the shafts 29 will be efficiently supported by a saddle member 34 in addition to the brackets 28, and a disengagement of the gears 31 and 27 is rendered impossible by virtue of the support provided at their inner end by the saddle member 34 and the brackets 36.

Finally with a view of permitting any one of the fans being cut off from operating without in the least affecting the operation of the remaining fans it will be seen, as in Figures 1 and 4, that each of the brackets 36 is carried by a preferably screw threaded stem 37 cooperating with a similar screw threaded opening in the housing 13, so that if the operation aforementioned is to be accomplished this may be achieved by simply moving one of the stems 37 to drop the bracket 36 associated therewith, to thus cause a disengagement of the teeth of the burr gear from the teeth of the gear 27.

Thus all of the objects of my invention have been accomplished and it will further be understood that numerous modifications of structure might readily be resorted to without in the least departing from the scope of my claims; which are;

1. The combination of a plurality of fans disposed at an angle to each other on horizontal axes, an electric motor arranged with its armature shaft vertical for rotating all the fans, controlling devices for inclining one or more of such axes from the horizontal at will, and controlling devices for operatively disengaging one or more of said fans from said actuating means at will.

2. The combination of a plurality of fans disposed at an angle to each other on horizontal axes, an electric motor arranged with its armature shaft vertical for rotating said

fans, means for relatively redisposing the axes of said fans without disengaging said actuating means, and means for redisposing the axis of one of said fans to disengage 5 said actuating means from the last-mentioned fan.

3. The combination of a plurality of fans disposed at an angle to each other on horizontal axes, an electric motor arranged with 10 its armature shaft vertical for rotating said fans, means for relatively redisposing the

axes of said fans without disengaging said actuating means, and means for redisposing the axis of one of said fans to disengage 15 said actuating means from the last-mentioned fan, both the two means last mentioned including in common a toothed gear driven by said actuating means and a toothed gear fixed relative to the fan last mentioned.

JOSEPH ARONOFF.
